BOTTLE-CAPPING MACHINE.

1,170,241.

Specification of Letters Patent.

Patented Feb. 1. 1916.

Application filed February 25, 1915. Serial No. 10,490.

To all whom it may concern:

Be it known that we, JOHN J. GAYNOR and PETER CARL LIEBER, citizens of the United States, and residents of Indianapolis, county of Marion, and State of Indiana, have invented a certain new and useful Bottle-Capping Machine; and we do hereby declare that the following is a full, clear, and exact description thereof, reference being had to the accompanying drawings, in which like letters refer to like parts.

The object of this invention is to improve the construction of means in bottle capping machines for preventing the chipping off of the lip of the bottle by the throat of the crowning plate, particularly after the plunger mechanism has worn so as to permit the mouth of the bottle to enter the throat too far. This is an improvement over the construction shown and described in our former application, Serial No. 797,554, filed October 27, 1913, for bottle capping machines.

One feature of the invention consists in placing a spring within a sleeve or barrel located between the spring and the casing, and holding the spring in place around the plunger. This holds the spring from buckling or bending laterally and holds it truly in place and causes a certain and regular action of the spring.

Another feature of the invention consists in improved means for limiting the upward movement of the plunger.

The full nature of the invention will be understood from the accompanying drawings and the following description and claims.

In the drawings, Figure 1 is an elevation of a bottle and the upper part of the bottle support and a central vertical section through the crowning head. Fig. 2 is a section on the line 2-2 of Fig. 1.

In the drawing 10 indicates a bottle for which a support 11 is provided, the upper end of the bottle projecting into the rigid tapering throat 12 of the crowning head plate 13. As shown in Fig. 1, the bottle is in position to have a crown 14 applied thereto, the bottle support 11 and crowning head being relatively movable as is usual in this class of machines as will be readily understood by those skilled in the art. As will be seen from the drawing the spring encompassing sleeve on the plunger is in en-

gagement with and stopped by the plug 19 to positively limit the upward movement of the plunger at the instant that the throat 12 of the capping plate 13 limits the upward movement of the cap and mouth of the bottle 10. Within the casing 15 extending upward from said head plate there is a centrally located plunger 16. Said plunger has a shoulder near its lower end below which a contracted portion of the plunger 65 projects through a vertical opening concentric with the throat 12, but of smaller diameter than said throat, as shown. Above the shoulder 17 a spiral spring 18 acts downward, said spring surrounding the plunger 70 and engaging the plug 19 which screws into the upper end of the casing 15. Therefore, said plug 19 is vertically adjustable and by it the tension of the spring 18 may be regulated and the upward movement 75 stopped.

A sleeve or barrel 21 surrounds the spring 18 and lies between it and the casing 15 and rests upon the lower shoulder 17 of the plunger, but stops at a point somewhat below the plug 19 near the upper end of the plunger so as to permit ample compression of the spring. A lock nut 22 is screwed on the plug 19. The casing 15 and screw plug 19 are arranged so that the plunger will 85 have only a slight movement and the upward movement is yieldingly limited by co-operation of the spring and the plug 19. As the throat and plunger wear, the wear is taken up by screwing down the plug 19 90 accordingly.

The invention claimed is:

1. A bottle capping machine including a relatively movable capping plate and bottle support, said capping plate being provided with a tapering throat, a plunger for discharging the bottle and cap with its lower end projecting through the capping plate into the throat thereof, adjustable means for positively limiting the upward movement 95 of the plunger at the instant that the throat of the capping plate limits the upward movement of the cap and mouth of the bottle, said adjustable means including a sleeve inclosing a portion of the plunger, 100 a spring encompassed by said sleeve to normally hold the lower projecting end of said plunger within the said tapered throat of said capping plate.

2. A bottle capping machine including a 110

- relatively movable capping plate and bottle support, said capping plate being provided with a tapering throat to receive the cap and mouth of a bottle to positively limit the inward movement thereof, a casing extending upwardly from said plate, a plunger within said casing, means arranged in connection with the plunger for positively limiting the upward movement of the plunger at the instant that the throat of the capping plate limits the inward movement of the cap and mouth of a bottle, and a spring acting on said plunger to resiliently hold the same in effective engagement with a bottle cap until the instant that the inward movement of the cap and the upward movement of the plunger is positively limited.
3. A bottle capping machine including a relatively movable capping plate and bottle support, said capping plate being provided with a rigid throat to receive the cap and
- 5 mouth of a bottle to positively limit the inward movement thereof, a casing extending from said plate, a plunger in said casing, means for positively limiting the upward movement of the plunger at the instant that the rigid throat of the capping plate limits the inward movement of the cap and mouth of a bottle and a spring acting on said plunger to resiliently hold the same in effective engagement with a bottle cap until the instant that the inward movement of the cap and the upward movement of the plunger is positively limited. 25
